COUCH OR SIMILAR ARTICLE

George H. Sanderson, 98 Walworth Ave.,
Scarsdale, N.Y. 10583

Filed Dec. 29, 1967, Ser. No. 9,984

Term of patent 14 years

Int. Cl. D6—01

U.S. Cl. D15—11

FIG. 1

FIG. 2

FIG. 3

FIGURE 1 is a perspective view of a couch or similar article showing my new design;

The dominant features of my design reside in those portions shown in full lines on the drawings.

I claim:

The ornamental design for a couch or similar article, as shown and described.
